UNITED STATES PATENT OFFICE

SEWARD B. JACKSON, OF CHATHAM, NEW JERSEY

DESIGN FOR A BUILDING

Application filed January 16, 1931. Serial No. 38,329. Term of patent 7 years.

To all whom it may concern:

Be it known that I, SEWARD B. JACKSON, a citizen of the United States, residing in the borough of Chatham, in the county of Morris and State of New Jersey, have invented a new, original, and ornamental Design for Building, of which the following is a specification, reference being had to the accompanying drawings, forming a part hereof.

In the drawings,

Fig. 1 represents a perspective view of the building embodying my new design, as viewed from the front, and

Fig. 2 represents a perspective view of the building embodying my new design, as viewed from the rear.

I claim:

The ornamental design for a building, as shown.

SEWARD B. JACKSON.
